(57) **CLAIM**

The ornamental design for a wireless presenter, as shown and described.

DESCRIPTION

FIG. 1 is a front, top and right side perspective view of a wireless presenter, showing my new design;

FIG. 2 is a rear, bottom and left side perspective view shown with an element in an alternate configuration;

FIG. 3 is a rear, bottom and left side perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the wireless presenter that form no part of the claimed design.

1 Claim, 9 Drawing Sheets
